[57] CLAIM

The ornamental design for a battery charger, as shown
and described.

DESCRIPTION

FIG. 1 is a perspective view of the top, front and right
side of a battery charger showing my new design;
FIG. 2 is a perspective view of the bottom, rear and left
side thereof;

FIG. 3 is a perspective view of the top, front and right
side of a second embodiment of a battery charger showing
my new design; and,

FIG. 4 is a perspective view of the bottom, rear and left
side of the battery charger shown in FIG. 3.

*FIG. 1**FIG. 2**FIG. 3**FIG. 4*
